TENNIS-RACKET FRAME.

1,131,418.

Specification of Letters Patent.

Patented Mar. 9, 1915.

Application filed December 1, 1914. Serial No. 875,030.

To all whom it may concern:

Be it known that we, MILTON B. REACH and WILLIAM RICHEY, citizens of the United States, residing, respectively, at Springfield and Chicopee, Massachusetts, have invented certain new and useful Improvements Relating to Tennis-Racket Frames, of which the following is a specification.

It is the object of our invention to provide a tennis racket frame of a multi-part construction, *i. e.*, of a plurality of strips glued together, the construction giving rise to a number of advantages as will appear hereinafter.

15 The invention consists in the features and combination and arrangement of parts hereinafter described and particularly pointed out in the claims.

In the accompanying drawing: Figure 1 is a plan view of the frame; Fig. 2 is a sectional view across the handle; and Fig. 3 is a cross sectional view through the upper part of the frame; Fig. 4 is a plan view of a modified form of frame; Fig. 5 is a cross 25 sectional view of the handle of Fig. 4; Fig. 6 is a cross sectional view through the upper part of the frame of Fig. 4.

Referring to Figs. 1 to 3, the main part of the frame is indicated at 1, and the handle at 2. These parts are usually made up of a strip of wood as ash, the two end portions of the strip being brought together and forming the handle. Difficulty has been experienced heretofore in producing good ash frames to given weights, the tendency being to have an excess of weight. In carrying out the present invention, instead of using what may be termed a one piece strip, we employ two strips such as 3, 4, and join them along an inclined or diagonal line as indicated at α . By using two or more strips, one of them may be of ash and the other of a lighter wood, and yet by making the frame and handle of a plurality of strips glued together, the necessary strength will be obtained. With this two or more part construction, the neutral strength of lamination is secured and increased strength is obtained because of the increased area of gluing surface due to the diagonal juncture between the two strips.

In making up the frame, the two strips are supplied with glue between their inclined or diagonal meeting faces and pres-

sure is then applied by which one part is forced with a wedging action upon the other, thus insuring perfect contact throughout the wedging or inclined surfaces and securing a perfect joint at all points.

It will be seen from the cross sectional view of the handle that the two ends of the one strip are indicated at 3, 3, and the two portions of the other strip are shown at 4, 4. The glue is applied to the surfaces in the handle at a , b , c .

In the manufacture of the above described frame, a strip of wood of rectangular cross section is first formed, and then it is machined, that is to say, we take a one piece strip of cross sectional shape and form or bend it into the general shape shown in Fig. 1. The strip is then machined, that is, it is cut on the substantially diagonal line $x-x$ of Fig. 3 to divide it into two strips 3, 4. These strips are then finished or smoothed, and then two strips such as 3, 4, are united with each other. In this action glue is applied to the inclined faces of the strips, and the outer strip or member is held in a form or clamp, and the inner member is forced vertically under pressure into wedging contact with the outer member, and then the parts are held and allowed to set.

Referring to Figs. 4, 5 and 6, which show another form of the invention, 5 indicates the outer strip, and 6 an inner strip, the former being made with a channel 7 on its inner face, the sides or walls of which are inclined and divergent from their meeting point or apex to the inner face of the strip. The other strip is shaped as a complement of the first strip, it having inclined surfaces 8 meeting at 9 forming a raised wedge-shaped surface adapted to fit into the correspondingly shaped channel of the strip 5. Glue is applied to the meeting surfaces of the strips and upon pressure being applied, one strip is wedged into close contact with the other and a tight joint is made throughout the extent of the meeting surfaces. The outer strip may be of ash, and the inner one may be of lighter material, and thus any given weight may be obtained, avoiding the objection of the frames running heavy in their manufacture when made entirely of ash. In making this form of the invention, each strip 5, 6, is made or machined separately in its lengthwise form. They are

then tied or otherwise held together and placed in a steam tank in their straight form. After they have become soft and flexible, they are conjointly bent around an iron form, *i. e.*, while still held together. They are then clamped and placed in a dry kiln until thoroughly set in this bent form. After this the strips are separated, and their inclined surfaces are coated with glue, and 5 then the inner member is expanded into perfect contact with the outer piece, in which position they are clamped and the glue allowed to set. In this form of the invention in which the one strip interlocks with the 10 other by an inclined portion on one extending into a corresponding recess in the other, the joining of the two strips can be made readily, as one will naturally assume proper relation in respect to the other. Furthermore, in this construction the objection experienced in bending a single strip of the 15 full size in cross section will be avoided. In bending such full size strip the fibers of the wood are liable to be distorted or ruptured 20 at, for instance, the points *y*, owing to the sharpness of the bend at these points, but with the two part construction each strip, being thinner than the full thickness of the combined strip, will bend without rupture 25 or breaking of the fibers, and the inner strip 30 will be free to creep on the outer strip.

In both forms of the invention one member of the frame is wedged into contact with the other, and in both forms extended surfaces are provided for gluing the parts together.

We prefer to form a channel at *x'* in one strip so that when the two strips are brought together, the channel will in effect provide a 40 hollow or air space within the frame and handle.

We claim as our invention:—

1. A tennis racket frame consisting of a plurality of strips having contacting faces 45 inclined in respect to the outer faces of said frame and glued together, substantially as described.

2. A tennis racket frame consisting of a plurality of strips having contacting surfaces inclined in respect to the outer faces 50 of said frame, the handle having its two sides glued together and each side having its two strips glued together along inclined surfaces, one strip having its sides wedged in between the sides of the other strip, substantially as described. 55

3. A tennis racket frame comprising two or more pieces having inclined faces, in wedging contact, with glue between said inclined faces uniting the pieces together, substantially as described.

4. A tennis racket frame comprising two strips, one of which is formed with a channeled face and the other of which is formed with a protuberant portion to fit said channel, the two strips being glued together along the faces of their intermeshing portions. 65

5. A tennis racket frame comprising two strips, one of which is formed with a wedge-shaped channel and the other of which is formed with a protuberant wedge-shaped portion to fit said channel, the two strips being glued together along their inclined 70 contacting surfaces, said strips having a free 75 space between their adjacent faces, substantially as described.

6. A tennis racket frame comprising two strips, one of which is formed with a wedge-shaped channel and the other of which is 80 formed with a protuberant wedge-shaped portion to fit said channel, the two strips being glued together along their inclined contacting surfaces, said channel and wedge-shaped portion having their apices directed 85 in the plane of the frame.

In testimony whereof, we affix our signatures in presence of two witnesses.

MILTON B. REACH.
WILLIAM RICHEY.
